UNITED STATES PATENT OFFICE.

CORREL W. JOHNSON, OF NEW YORK, N. Y.

SOUND CLARIFIER.

Application filed June 15, 1922. Serial No. 568,586.

To all whom it may concern:

Be it known that I, CORREL W. JOHNSON, a citizen of the United States, and resident of the city of New York, borough of Manhattan, county of New York, and State of New York, have invented a new and Improved Sound Clarifier, of which the following is a full, clear, and exact description.

My invention relates to a sound clarifier, and aims to provide certain new and useful improvements in connection with a device of this character and more particularly over my prior Patent No. 1,240,050 of September 11, 1917, as well as my previous application No. 367,412 of March 20, 1920, it being further an object of this invention to provide a device of the character stated which may be more desirable for use in certain applications than the structure described in my co-pending application Serial No. 568,587, filed June 15, 1922, entitled "Sound clarifier."

More particularly with respect to the construction noted in my previous application Serial No. 367,412 filed March 20, 1920, it has been found that certain objections have arisen in connection with the mounting of the auxiliary horns, as well as the propagation of the sound waves therethrough.

Thus it is an object of the present invention to provide a sound clarifier which is particularly intended for use in connection with talking machines although not necessarily limited to this particular application, and by means of which a device of this nature may be constructed in an extremely simple and economical manner.

A further object of the present invention is that of providing a sound clarifier in which any auxiliary horns or tubes will be supported in a manner more desirable, and in which however, the sound waves will be introduced into these members to achieve a better result.

With these and further objects in mind the present invention has reference to a sound clarifier including an amplifying chamber within which means is provided permitting of the accomplishment of the results set forth.

In the attached sheet of drawings it will be seen that a practical embodiment of my invention has been shown in these drawings.

Figure 1 is a sectional side view of a talking machine cabinet and showing my improved type of clarifier in association therewith, and

Figure 2 is a sectional plan view taken along the line 2—2 and in the direction of the arrows indicated in Figure 1.

In these views it will be noted that the reference numeral 5 indicates the lid of the cabinet 6, which latter houses the turn table 7, and reproducer 8 co-operating therewith, this latter element being supported by the tone arm 9 which is in turn connected to my improved type of clarifier.

Referring to the construction of the latter it will be noted that the same embraces a neck 10 or sound conveyor 10, and an amplifying chamber 11, these members being formed by two separate elements, if it is so desired. Also contrary to conventional construction it will be seen that I prefer to graduate the walls of the sound conveyor to a relatively great thickness adjacent the outer end of this member as has been indicated at 12, and these thickened walls are preferably provided at opposite points in the tone conveyor, and each present dual passages 13 extending generally in the same direction as the bore of the passage of both the conveyor and amplifying member.

Each of the passages embraces a flaring mouth 14 so that a portion of the sound waves will be diverted into each passage in their outward course through the sound conveyor, and these diverted sound waves are conducted in a manner hereinafter described, through tubes 15 into horns or deflectors 16.

It will further be seen that the inner surfaces of the walls of the sound conveyor adjacent its outlet present sufficient body to support the tubes 15 which are suitably connected thereto, it being further noted that I prefer to extend and incline the thickened walls 12 of the sound conveyor beyond the tubes 15, as has been indicated by the reference numeral 17 whereby to meet and merge into the walls of the amplifying chamber to provide a gradual expanse of the sound waves in their propagation.

It is to be noted that the flaring mouths of the auxiliary openings or passages 13 are inset in both side walls of the sound conveyor and lead to a converging and concave formation in their outlet, and the inset edges being rounded a smooth passage is provided for the air motion conveying the sound waves. As in Figure 2, the auxiliary outlets 110 are individually connected with the tubes which extend into the side walls of the de-

flector, and thus it will be appreciated that these deflectors or horns 16 receive their only support through the medium of the tubes 15.

Now with a view of preventing a distortion or improper projection of the sound waves from within the horns 16 it will be noted that, I preferably provide a deflecting and dividing wall 18 in each of the same which has its outer end 19 extending at a point substantially intermediate its side edges for a distance covering and beyond the tube openings for the purpose of providing a gradual coalescence of the sound waves entering each horn from the individual tubes thereby avoiding agitated air motion to destroy the wave motions resulting from abrupt coalescence.

Thus the objects of this invention have been accomplished and it will be appreciated that numerous modifications of structure

might readily be resorted to without in the least departing from the spirit of my invention which I claim as:

A sound clarifier, including an amplifying member, a pair of deflector horns within 25 said member disposed one above the other, a deflector member within each of said horns, a pair of tubes connected to each of said horns and opening into the rear end of each of said deflector horns, sloping walls on said deflector member within each of said horns associated with the tubular opening to direct the sound forward within the horn, and a plurality of passages formed in the walls of the amplifier member, the inner ends of 30 said tubes being mounted in the wall in line with the outer ends of said passages, whereby the tubes and the arms are supported from the walls of the amplifier member. 35

CORREL W. JOHNSON.
